UNITED STATES PATENT OFFICE.

HOWARD BROWN, OF SPRINGFIELD, MASSACHUSETTS.

MACHINE FOR MAKING LOOSE-LEAF LEDGER-PAPER.

1,231,698.

Specification of Letters Patent.

Patented July 3, 1917.

Application filed August 1, 1913. Serial No. 722,511.

To all whom it may concern:

Be it known that I, HOWARD BROWN, a citizen of the United States, residing at Springfield, in the county of Hampden and State of Massachusetts, have invented new and useful Improvements in Machines for Making Loose-Leaf Ledger-Paper, of which the following is a specification.

It is the object of the present invention to provide a machine suitable for use in the manufacture of loose leaf ledger pages, having near the hinged portion of those pages an area specially treated to make the sheet more pliant and more readily adapted for bending when in the ledger, without wrinkling or puckering at the bend.

The machine treats the paper while it is still in a continuous strip or web and preferably while still in the paper making machine and under definite and rather exacting physical conditions, such as dampness and plasticity. The paper sheet or web under treatment is first nicely adjusted to the conditions at hand and then passed through between rollers, where it is subjected to a localized compression to bring the fibers close together along certain predetermined lines, without substantial displacement or fracture of the fibers, thereby not only reducing the thickness of the sheet at the treated areas, but also changing its physical structure and increasing its density and making it more pliant at these areas, so that after the web is cut up into ledger sheets, those sheets are readily bent near the hinged portion without wrinkling or puckering. After this compression at the rolls, the paper web passes to a drier drum and then to succeeding drier drums, moving at a rapid rate and there the heat of the drums so fixes or bakes the web structure, that the sheet retains permanently the effect of its severe and momentary compression at the rolls.

45 In the accompanying drawings:

Figure 1 is a side elevation of the roller mechanism through which a web of paper may be passed continuously to receive the special treatment here contemplated.

50 Fig. 2 is an end elevation of the rolls

showing their position adjacent to the first and second drier drums of a paper making machine.

Fig. 3 is a perspective view of a ledger sheet treated in the machine, here disclosed.

The apparatus shown in Fig. 1 comprises a pair of standards 1 and 2 slotted at their upper ends to receive the bearing blocks of the lower roll 3. This roll is of hard inelastic material, preferably metal and is driven in suitable manner, as through a clutch 4 and pinion 5 from a gear 6, which may be one of the gears of the paper making machine. The speed of rotation of roll 3 is such that the sheet of paper 7 passes over the roll at a speed corresponding to the surface speed of the drier drums, with which this device is associated.

The relative locations of the drier drums are indicated in Fig. 2 where drum 8 may be considered as the first drier drum of the series receiving the web of paper as it comes from the press rolls of the machine and delivering it over roll 3 for treatment, after which the paper passes directly to the next drier drum 9 so that the heating and drying action of that drum may serve quickly to fix in the paper, the compressing effect set up at the rolls. The drying drums may be of usual construction with a felt 10 holding the paper web in close contact with the steam heated cylinders of the drier during its rapid movement through this stage of the machine. The paper may then pass to other drying drums in usual manner and finally through calender rolls, as in ordinary practice. The calendering operation, does not disturb the beneficial effect of compacting the fibers locally and leaves these compacted areas substantially unaffected.

Mounted above roll 3 with its bearing blocks 11, and 12 slidably positioned in the slotted standards 1 and 2, is a roll or shaft 13, which may be relatively small in diameter and on which a plurality of disks 14 are mounted. These disks are hard and inelastic and may be of brass or of iron or the like, with suitable collars 15, and clamping bolts 16. They preferably are adjustable along the shaft 13 to vary the distance between

the treated areas on the paper web. The total length of shaft 13 may vary, but may be long enough for use on an eighty inch paper machine, the disks 14 being sufficient in number and so spaced as to yield paper cutting to advantage commercially. With shaft 13 as long as this, there is a tendency for the shaft to bow up in the middle or to whip under the heavy pressures which must be applied, and to counteract this tendency and to equalize the pressure throughout the entire width of the sheet, use is made of a weighting roll 17 surmounting the disks 14 and resting directly thereon, with its trunnions housed in bearing blocks 18, slidably mounted in standards 1 and 2 and held down by stud 19, which passes freely through the cross bar 20, surmounting each standard, but is provided with a hand wheel 21 threaded on the stud in such a way that by turning the wheel, the stud may be raised through the cross members 20 to lift bearing block 18, thereby to lift the weight roll 17 away from the disks 14. Weighted levers 22 (Fig. 2) may be provided for each standard to increase the effective pressure of the weight roll 17 on the disk.

The disk carrying shaft or roll 13 is rotated at the same peripheral speed as roll 3 by means of a suitable gear 23 and also is capable of longitudinal shifting through the action of a hand wheel 24 mounted to turn a shaft 25, whereon is carried a yoke 26, the arms of which fit in an annular groove 27 cut in the end of shaft 13. It sometimes happens in practice, that the paper strip 17 shifts slowly in its position on roll 3 longitudinally thereof and in order that the compressed areas may be properly located on the sheet, it is desirable to shift the disks, as above recited, to the same degree.

In using the apparatus here disclosed, it is desirable that the material under treatment, be brought to proper physical condition before the pressure is applied, as otherwise either the impression will not be retained or there will be destructive crushing and fracture of the fibers. The initial production of the paper web may be in accordance with standard practice, as for instance on a Four-drinier machine and when that continuous strip comes from the press rolls to the first drum of the drier, it is damp and somewhat plastic and the fibers which make up its structure are matted together as a porous mass, substantially uniform in thickness and homogeneous in structure. At the first drier drum, the heat of the drum and the development of water vapor or steam in the web, as the result of that heat, acts to temper the mass of fiber and while removing some of the excess moisture, leaves the structure in pliant condition, best suited for the severe compression which it must undergo at the

next stage of its treatment. In this porous and loosely matted condition, with the fibers tempered and plastic, the sheet passes through over roll 3 and, under the disks 14 and there for a brief instant is subjected to extreme pressure along predetermined lines, the areas thus compressed having their fibers compacted, but without breaking or destruction and with substantially no displacement of the fibers other than that incident to this compacting. The pressure thus momentarily applied, is extreme, higher than could be applied safely for prolonged periods and after this momentary compression, the paper goes almost instantly to the second drier drum and then on around succeeding drums, the action of these drums serving to fix or bake in the effect produced by the disks, stiffening up the fiber structure and rendering the sheet firm and hard for delivery to the calender rolls. It thus results that areas which have undergone extreme compression and quick baking, are still in the paper when it reaches the calenders and are not disturbed in the calender rolls, but remain characteristic features of the sheet. Ultimately the long web of paper with its longitudinally extending treated areas may be cut up into ledger sheets of the general character shown in Fig. 3 with the treated areas extending across to constitute the hinge or bending portion of the sheet. This hinge or condensed portion of the sheet gives the paper more flexibility and the book made up of these sheets when open, will lie flat and in convenient position for use.

I claim:—

1. In combination with the heater drums, of a paper making machine, a pair of standards adjacent thereto, a pair of rolls carried by said standards, the topmost of said rolls bearing impression disks, means for positively driving both of said rolls, the topmost of said rolls being vertically adjustable in said standards, a weight roll supported to bear on said disks and weighted arms cooperating with said weight roll to govern the pressure of said disks on the paper.

2. In a paper machine, the combination of a pair of standards, bearing boxes supported by said standards, a pair of rollers mounted in said boxes, the topmost roll and its boxes being adjustable in said standards and carrying a plurality of rigid impression disks, a weight roll bearing on said disks to equalize the pressure thereof on the paper web, and yielding means adjustably controlling the pressure of said disks on a continuous web of paper supplied over the lower roll.

3. The combination with a paper making machine, of a backing roll, a hard disk, means for causing the disk to bear with a heavy pressure against said backing roll, said backing roll and disk being located in

advance of one of the driers of said paper making machine, whereby the web passed between said roll and disk will be compacted and condensed along a predetermined strip 5 or stripe therein before it is completely dried.

In witness whereof, I hereunto subscribe

my name to this specification in the presence of two witnesses.

HOWARD BROWN.
